CLAIM

The ornamental design for a filter cover for powered air purifying respirator, as shown and described.

DESCRIPTION

FIG. 1 is a front perspective view showing the new design for a filter cover for powered air purifying respirator;

FIG. 2 is a front view thereof;

FIG. 3 is a back view thereof;

FIG. 4 is a top view thereof;

FIG. 5 is a bottom view thereof;

FIG. 6 is an enlarged left side view thereof; and,

FIG. 7 is an enlarged right side view thereof.

The broken lines enclosing portions of the article are included for the purpose of illustrating structure that is not part of the claimed design.

The shading is provided to illustrate contour only and is not an indication of surface texture.
